HARVESTER AND STOOKER.

Application filed August 3, 1921. Serial No. 489,618.

In the specification the term "binder" means a modern harvester commonly known as a binder; the term "binder-head" refers to all that portion of the binder which shifts 5 forward or backward when adjusting the binding apparatus to the various lengths of grain, the term "stooker" refers principally to those portions which, in addition to the binder, are required to make the stook and 10 operate the stooking apparatus most of which in this invention are supported on special frame work which also supports the binder head and shifts forwards and backwards with the binder head; the term "machine" refers to the combined binder and 15 stooker.

The objects of our invention are, first, to improve the modern binder by having the binder head and elevators sufficiently high 20 that the sheaves will fall into a receiver; second, to provide the said receiver of sufficient size and form to contain sufficient sheaves for a stook; third, to provide means for dropping the front end of the receiver in a manner 25 that will deposit the sheaves on the ground and form a stook; fourth, to open the receiver in the middle, one piece swinging to each side to clear the stook as the machine moves forward; fifth, to bring the receiver to its former position to receive another supply of sheaves, and sixth, to provide means to support a sheaf which may be bound while the receiver is in a lowered 30 position.

Referring now to the drawings in which like characters of reference indicate corresponding parts in each figure,

Figure 1 is a top plan view of the complete machine.

Figure 2 is a section on line 2—2 of Figure 1.

Figure 3 is an end view.

Figure 4 is an enlarged detail of the dumping operating mechanism.

Figure 5 is an enlarged detail of the trip mechanism and sheaf counter,

Figure 6 is an enlarged top plan view of the basket or sheaf receiver.

Figure 7 is an end view of the basket or sheaf receiver in dump position.

Figure 8 is a side elevation of the basket.

Figure 9 is a detail of a stop disc.

Figure 10 is a detail of the clutch mechanism.

Figure 11 is another detail of the clutch mechanism.

Figure 12 is a detail of the sliding shaft and gear.

Figure 13 is a detail of the rollers at the top of sliding frame.

Figure 14 is a detail at the bottom of the sliding frame.

In the drawings 1^a designates the machine frame supported on the driving wheel 1 and tongue trucks 81 and a grain wheel (not shown). The machine is provided with the usual cutter bar 84 and moving canvas platform 16, on which the grain when cut is deposited and which conveys it to the space 17 between the two elevator conveyors 17^a and 17^b. At the top end of these conveyors and supported on the frame, well above the driving wheel, 1, is the receiving deck 50 on to which the grain is delivered from the conveyors 17^a and 17^b and from whence it travels downwardly by gravity to be bound in well known manner by a sheaf needle 36 and knotter 74. The grain so bound into a sheaf is delivered from the deck 50 in the usual manner. Situated below the deck 50 and adjacent thereto is the sheaf receiving basket 56^a formed with two sections or wings 56. This basket is adapted to operate on the stationary bar 55 by means of bell cranks, the operation of which is hereinafter more fully 50 described.

Mounted on the axle 6^a of the driving wheel 1 is a sprocket wheel 6 connected by a chain 8 to a sprocket wheel 7 on a longitudinally extending shaft 9, suitably journaled in the machine frame. This shaft at one end is provided with a bevelled gear 10 adapted to mesh with a pinion gear 11 on a transversely extending shaft 12, having at the outer end a crank 13 adapted to operate 90 the sickle. This shaft 12 is also provided, at its other end, with a sprocket wheel 14 which by means of a chain operates the platform conveyor and the elevator conveyors 17^a and 17^b. 100

It will thus be seen that when the machine moves forward the driving wheel 1 will operate the sickle through the sprocket 6, chain 8, sprocket 7, shaft 9, bevelled gear 10, pinion 11, shaft 12 and crank 13 and also through sprocket 14, the platform conveyor and elevator conveyor 17^a and 17^b. Also mounted on the shaft 12 is a second sprocket wheel 18 connected by a chain 85 and sprocket wheel 19 to a transversely extending 105 packer shaft 20, which operates the needle 36 in the usual manner. On the packer shaft 110

20 is a sprocket 21 connected by a chain 21^a to a sprocket wheel 22 on a counter or stoker shaft 23 whereby the latter is rotated when the machine is in operation.

5 The wings of the basket 56^a, previously described are adapted to swing on the bar 55 when operated by the bell cranks 58, the loops 59 permitting the required operation to take place, at the same time holding the 10 basket in suspended position in contact with the bar 55. On the stoker shaft 23 is a bevelled gear 24 designed to mesh with the gear 25, carried by a crank shaft 26. This 15 shaft is in turn connected by means of links 60 and bell cranks 58 to the end of each of the wings 56 of the basket so that when the crank shaft 26 makes a revolution it pulls the links 60 backward which by means of the bell cranks 58 pull the forward end of the 20 receiver downward thereby depositing the sheaves on the ground with the butt ends downward thus forming the stool. It should here be noted that the eye in the bell crank 58 supports the outer side of the wing 56 on the bar 55 while the loop 59 permits the inner side of the wing to drop downward by the force of gravity causing it to assume the 25 position shown in Figure 7 and also shown by the dotted lines in Figure 2, thereby allowing the said wings to straddle the stool 73 as the machine moves forward. This is the position when the crank shaft 26 has made only a half revolution; upon completing the revolution the bell cranks 58 are 30 forced forward and the two wings 56 return to their position to receive another supply of sheaves for the succeeding stool.

In order that the basket 56^a be conveniently operable, a rod or cable 44 is provided 40 connected by a chain 45 running over the pulley 46 to a point convenient to the driver's seat 83, where this rod can be operated either by foot or by hand. The pull of the 45 rod 44 forward disengages a dog 33, pivotally mounted at 33^a, from the trip 29 carried by the gear 24 and rotatably mounted on a pin 31 carried on the shaft 23. The trip 29 is spring actuated by means of a spring 30 and is, as illustrated in Figure 10, provided 50 with two projecting arms 32 and 34. Also mounted on the shaft 23 is a clutch member 28 formed with friction roller lugs 27. This member is adapted to rotate with the shaft 23, while the pinion 24 thereon remains stationary and the receiver or basket is in position, the shaft 23 rotating in the hub of said pinion 24.

From the foregoing it will be seen that 60 when the rod 44 is operated to release the dog 33 from the trip 29, the spring 30 will draw it forward as it rotates on the pin 31, till the arm 34 presses against the hub (see Figure 10) thereby raising the arm 32 against the hub so that the friction roller lugs 27 will engage it and cause the pinion 65

24 to revolve with the shaft 23 thereby operating the gear 25 and crank shaft 26 to the extent of one complete revolution, the number of teeth in the bevelled gear 25 being a multiple of the number of teeth in the pinion 24. To prevent the forward ends of the basket wings from spreading, until they have lowered to the position of depositing the sheaves on the ground, we provide on the frame at 53 and 54, supports to hold the 70 guides 64 in position. Also secured on the top edges of each wing of the receiver or basket are anti-friction rollers 66 adapted to engage with the guides 64 (see Figure 8) permitting the wings to slide according 75 to the formation of the lower ends of the guides. In the return travel of the basket the rollers 66 travel on the guides 64 upwardly to close the links (as shown in Figure 6). To prevent the sheaves from being 80 caught in the opening between a portion of the two wings of the basket instead of eyes we provide a piece of canvas or other flexible material 57 to span this opening so arranged 85 that when the wings 56 assume the position as shown in Figure 7, this flexible material 57 is folded up.

To prevent the crank shaft 26 from turning backward when it should be at rest, we provide on the frame at 63, Figure 8, a member 61, spring retained by the spring 62 and designed to act as a lock for the crank shaft 26.

Referring now more particularly to Figure 4, 47 is a cam mounted on the shaft 26 and provided with an anti-friction roller 48.

This cam permits the shaft 26 to make one complete revolution before being again engaged by the member 33. When the basket 56^a is required to be operated, the driver will exert a pull on the chain 45, which will cause the member 33 through the cable 44 to disengage the cam 47, at the same time the arm 29 will be disengaged permitting the spring actuated members 32 and 33 to spread as shown in dotted lines in Figure 10, thereby 100 engaging the stops 27 on the clutch 28.

The gear 24 which is loosely mounted on the shaft 33 will then rotate, operating with it the gear 25 and shaft 26. As the shaft 115 26 completes a revolution, the roller 28 on the cam 47 will again engage the member 33 preventing a further rotation. Simultaneous with this operation, the member 33 will engage the arm 29, which will disengage the members 27 of the clutch 28.

Mounted on the frame 54 is a substantially L-shaped supporting arm 67. Pivotaly connected to this arm at 72 is the member 67^a, which is provided with fingers 68 and designed to be retained in position by a chain 71 engaging the loop in the fingers and travelling over the pulleys 69 and 70 and connected at its other end to the wing 56 of the basket, as illustrated in Figure 2, from 120 125 130

which it will be seen that as the basket lowers to deposit the stook the chain 71 is slackened and the fingers through force of gravity assume the position, shown in dotted lines in Figure 2, to catch any sheaf which may be discharged before the basket returns to its position and then to drop it into the basket when it reaches its position.

The foregoing is a description of the stooker and its operation as combined with the remodeled binder when the receiver is dumped at will by the driver.

When it is desired that the machine should be made to automatically stook when a given number of sheaves are deposited in the basket, mechanism is provided for this purpose, as illustrated in Figures 4 and 5, in which 36, as previously mentioned, is the binder needle mounted to oscillate on a shaft 49 and adapted to operate in conjunction with the delivery of the grain from the deck 50. At the end of the rod 44, remote from the bevelled gear 24 thereon is a shaft 41 journaled on a bearing secured to the frame 51 and adapted to carry thereon a disc member 41 comprising three ratchet wheels rigidly fastened together. These wheels are each provided with notches in rotation, namely 7, 9 and 11 respectively as here illustrated, although the number of ratchet wheels in the disc and the number of notches in each wheel may be arranged at will. These notches are intended and do correspond to the number of sheaves in a stook and can be set accordingly. This is accomplished by a hand lever 39, adapted to engage with a notched segment 39^a to operate a dog 37 which in turn will engage with the teeth in one of the wheels in the member 41, as illustrated in Figure 5, by which it will be seen that when the needle 36 returns to rest it will engage with the dog 37 in one of the notches in the member 41 turning the latter one notch. This operation will be repeated at the completion of each sheaf. The dog 37 is returned by means of a spring 38 and as the disc member 41 completes its rotation the designated number of sheaves fall into the basket and on the arrival of the last sheaf the pin 42 forces a dog 43, connected to the rod or cable 44 and pivotally supported on a bracket 44^a of the frame, backwards immediately releasing it.

This action pulls the rod or cable 44 extending over the pulley 44^b forward automatically, automatically disengaging the member 33 from the cam 47 and the trip 29, the operation, previously described as performing the stook, being repeated.

The frame 1^a for carrying the binder head and stooker is illustrated chiefly in Figures 1, 2 and 3 and is slidably related with the rest of the machine.

The member 82 is supported by friction

rollers 80 on the side of the main frame, while the upper portion of the stooker frame is held in contact with the side 77 of the main frame and the far end of a lever 75 engages the member 78 on the binder head frame which the driver on the seat 83 may operate to suit the length of grain and lock the same with the dog of the lever in the notches 76. The rear end of the packer shaft 20 is square and slides in the square hole or bore of the member 19 when the binder head and stooker are shifted.

It will be noted that the binder head is much higher above the ground than is the case with the ordinary binder and that the binder head frame is slidably operable on the main frame and in order to facilitate this slidable operation the packer shaft 20 is formed square at the end, as illustrated in Figure 12.

It is obvious that many changes may be made in the arrangement and details within the scope of our invention.

What we claim as our invention is:

1. In a combined binder and stooker, a concave receiver divided at the bottom to receive the sheaves for a stook, means for turning the forward end of the receiver downward for the purpose of depositing the sheaves on the ground in the form of a stook, and means for spreading the two parts of the receiver by gravity at the lower end for the purpose of straddling the stook as the machine moves forward.

2. In a combined binder and stooker, a two-part receiver, means for turning the forward end of the receiver downward to deposit the sheaves in the form of a stook, means for operating the two parts of the receiver to straddle the stook, and means for retaining the said parts together, and means for actuating the receiver comprising a crank-shaft in combination with a link and bell-crank.

3. In a stooker having a receiver composed of two parts, bell-cranks arranged to hold the parts of the receiver together and in position, and loops to permit the two parts to spread by the force of gravity when lowered, all as and for the purposes described.

4. In a stooker, a two-part receiver, crank-shaft means for operating the receiver, and means for controlling the movement of the crank-shaft when the receiver is in position to receive the sheaves.

5. In a combined binder and stooker, a receiver, means for retaining the sheaves when bound, means for conveying the sheaves to the receiver, means for operating the stooker, and means adapted to engage with said means to regulate the number of sheaves in a stook and comprising ratchet wheels adapted to form a disc, a dog actuated by the binding apparatus and designed to engage

one of the ratchet wheels in said disc, and means on the disc adapted to engage with the operating means to operate the stooker.

6. In a combined binder and stooker, a frame, stooking mechanism and binder head supported on said frame, means for adjusting the frame forwards and backwards with respect to the binder, as and for the purpose specified.

7. In a combined binder and stooker, a ¹⁰ framework, means for shifting the framework, a binder head and stooker supported on said frame, anti-friction rollers adapted to reduce friction between the shifting parts in contact.

CHESTER E. STEARNS.
CHARLES H. VOGEL.
